(57) **CLAIM**

The ornamental design for a device for pick-up, handling and transport of hazardous waste and related paraphernalia, as shown and described.

DESCRIPTION

FIG. 1 is a top perspective view of a device for pick-up, handling and transport of hazardous waste and related paraphernalia;

FIG. 2 is a bottom perspective view of the device;

FIG. 3 is a front view of the device;

FIG. 4 is a rear view of the device;

FIG. 5 is a left side view of the device;

FIG. 6 is a right side view of the device;

FIG. 7 is a top view of the device; and,

FIG. 8 is a bottom view of the device.

1 Claim, 6 Drawing Sheets
